UNITED STATES PATENT OFFICE.

GEORGE AUSTIN BAKER, OF PHILADELPHIA, PENNSYLVANIA.

FUEL-VAPORIZER FOR INTERNAL-COMBUSTION ENGINES.

1,359,218.

Specification of Letters Patent. Patented Nov. 16, 1920.

Application filed October 23, 1919. Serial No. 332,633.

To all whom it may concern:

Be it known that I, GEORGE A. BAKER, a citizen of the United States, residing at Philadelphia, in the county of Philadelphia and State of Pennsylvania, have invented certain new and useful Improvements in Fuel-Vaporizers for Internal-Combustion Engines, of which the following is a specification.

10 One object of my invention is to secure an immediate flow of fuel gas to an internal combustion engine in cold weather by providing a structure which will operate to quickly vaporize the fuel so that the engine 15 during its initial movement will be supplied with a rich mixture of gas.

Another object is to so construct my invention that water which ordinarily would collect in the bottom of the carbureter will 20 flow or drip into the device of my invention so that if the latter is in operation it will vaporize the water with the fuel and it will not be necessary to draw off or drain the water as is usually the custom.

25 Another object is to so construct my invention that it will vaporize fuel which is less volatile than gasolene. For example my invention will operate to vaporize kerosene or petrol and when such latter mentioned 30 types of fuel are used, the vaporizing heat which is accomplished by means of electricity can be increased by means of a rheostat, for example by taking out resistance to the current so that sufficient heat is supplied to readily vaporize the fuel. Also the 35 operation of the rheostat will control the speed of the engine by causing a greater or less amount of the fuel to be vaporized.

A further object is to make my invention 40 of a simple and durable construction and so that it can be attached to carbureters of various types.

These objects, and other advantageous 45 ends which will be described hereinafter, I attain in the following manner, reference being had to the accompanying drawings in which—

Figure 1 is a sectional elevation showing my invention attached to a carbureter in 50 an operative position for vaporizing the fuel leading to the intake manifold of an internal combustion engine; the electrical connection being illustrated diagrammatically, Fig. 2 is a diagrammatical representation 55 illustrating how a rheostat can be included

as a part of the electrical connection, and Fig. 3 is a transverse section taken on the line 3—3 of Fig. 1.

Referring to the drawings, 4 represents a carbureter of a well known type which includes a hollow body portion or receptacle 5 providing a liquid fuel chamber 6, such for example as for holding gasolene, kerosene or petrol. I provide said chamber with a spider 6^a and a small upright tube 7 open at both ends; said tube being supported by the central portion of the spider 6 and having its top end above the level of the liquid fuel in the chamber 6 and its lower end positioned a slight distance above the bottom 70 of the chamber 6 as shown in Fig. 1. The top end of the tube 7 leads into a passage 8 communicating with the intake manifold 9 of an internal combustion engine. A transverse branch 10 provides a passage 11 which 75 communicates with the passage 8 and this passage 11 includes a butterfly valve 12 for controlling the entrance of air from the atmosphere into the passage 4 to mix with the fuel as it passes upwardly through the passage 8. The level of the fuel within the chamber 6 is controlled by means of a float 13 which is connected to a lever 14; said lever 14 being pivoted at 15 and having a needle valve 16 thereon for controlling an 80 entrance of the fuel through the inlet passage 17. A pipe 18 leading from a fuel reservoir (not illustrated) supplies the liquid fuel to the passage 17. The parts thus described with the exception of the construction and arrangement of the tube 7 and spider 6 do not in themselves form a part 85 of my present invention since they are of usual construction and operation.

The body portion 1 has a screw threaded 95 hole 19 in its bottom and this hole is usually provided for the connection of a drain or pet-cock to permit the draining of water which settles in the bottom of the chamber 6 and ordinarily this water must be drawn from the carbureter so that it will not pass in a body up the tube 7 instead of the fuel.

My invention also includes a container 20 which is connected by a screw threaded nipple 21 to the body portion 5 of the carbureter directly under or in vertical alignment with the lower end of the tube 7; said nipple being screwed into the hole 19. One end of a coil of wire 22 is clamped between the bottom of the nipple 21 and a ledge 23 110

in the upper portion of the container 20. The coil 22 extends through the space provided by the container 20 and the lower end of the coil is connected to a binding post 24; 5 said binding post extending through an insulating sleeve 25 and insulating washer 26 so as to be insulated from the body of the container 20; it being noted that the latter is made of metal.

10 One pole of a battery 27, or other suitable generator of electricity is connected by a wire 28 to the body of the container 20 while the other pole of said generator is connected by a wire 29 to the binding post 24. A rheostat 30, as shown in Fig. 2, is included in the wire 29 and serves both as a switch and as a means for supplying various amounts of current from the generator 27 to the coil 22. In some instances, for example where 15 gasoline or any readily volatile liquid fluid is used, I may merely include a switch 31 in the electric circuit as shown in Fig. 1 and in this instance a less powerful electric generator 27 can be employed. However, I prefer to use a rheostat 30 since by it I can 20 vary the amount or intensity of the electric current as supplied to the coil and can also use the rheostat as a switch for cutting off the current when the device is not intended 25 for use.

By suspending the container 20 by the nipple 21 to the bottom of the body portion 5, the liquid fuel from the chamber 6 will run into the container 20 and fill the same.

30 When electric current is passed through the coil 22 the latter will be heated and the liquid fuel within the container will be vaporized and changed into gas, and said gas will pass upwardly through the nipple 21 and tube 7 into the intake manifold 9. Thus even though the engine and its connected parts are cold, I am enabled to supply a rich mixture of gas to the engine merely by turning on the current to heat the coil 22.

40 While in actual practice I have found that the device is of great value in initially starting a cold engine I have also found that it is equally valuable during the normal operation of an engine since it provides a constant and rich supply of gas to the engine.

50 Also any water which ordinarily would collect in the chamber 6 flows into the container 20 and vaporizes with the fuel providing a mixture which is readily combustible and when my device is in use upon a carburetor it is unnecessary to draw any water therefrom and at the same time avoids any improper operation of the engine which might otherwise occur if water is permitted 55 to collect in the carburetor as above noted.

60 By positioning the tube 7 directly over the nipple 21 so that the fuel vaporized within the container will pass directly upward through the tube instead of being compelled 65 to pass through the entire body of liquid

fuel within the chamber 6 the gas which is vaporized is prevented from being mixed with or condensed by the body of liquid fuel within the chamber 6. In other words, with the construction illustrated, the fuel 70 which is vaporized or changed into a gas state will pass directly into the space above the level of the liquid fuel in the chamber 6 from where it will be taken into the manifold. I have illustrated the lower end of the 75 tube 7 spaced a short distance above the bottom of the chamber 6 in order to provide liquid fuel into the container. However, the small bubbles of gas which are vaporized will pass through the small body of liquid fuel between the lower end of the tube and the bottom of the chamber 6 without being condensed or without mixing with the liquid fuel for the reason that the gas bubbles will pass directly upward in a vertical direction 80 from the nipple into the tube 7 and will not remain in the body of liquid long enough for the liquid to condense them.

85 While I have described my invention as taking a particular form, it will be understood that the various parts of my invention may be changed without departing from the spirit thereof, and hence I do not limit myself to the precise construction set forth, but consider that I am at liberty to make 90 such changes and alterations as fairly come within the scope of the appended claims.

95 Having thus described my invention, what I claim as new and desire to secure by Letters Patent is:—

100 1. The combination with a receptacle providing a chamber for liquid fuel and having a gas take-off passage, of means for heating said liquid fuel at a position below the level thereof whereby gas is produced; and means 105 of comparatively small cross section for conducting said gas into said take-off passage so that the gas will be kept out of contact with the major portion of said liquid fuel; substantially as described.

110 2. The combination with a receptacle providing a chamber for liquid fuel and having a gas take-off passage communicating with the space above the level of liquid fuel within said chamber, of means for heating said liquid fuel at a position below the level thereof whereby gas is produced; and a tube within said chamber for conducting said gas into said space so that the gas will be kept free from contact with the major 115 portion of the liquid fuel during the movement of the gas toward said space; substantially as described.

120 3. The combination with a receptacle providing a chamber for liquid fuel and having a gas take-off passage communicating with the space above the level of liquid fuel within said chamber, of container adjoining the bottom of said chamber and communicating therewith whereby liquid fuel will pass from 125 130

said chamber into said container; means for heating the liquid fuel within said container to produce gas; and means positioned directly above the communicating portion of said container for conducting said gas upwardly to said space so that said gas will be kept free from contact with the major portion of the liquid fuel within said chamber during the movement of the gas toward

10 said space; substantially as described.

4. The combination of a carbureter having a fuel chamber provided with a hole; a nipple connected to said carbureter through the medium of said hole; a container connected to said nipple and having a ledge; a

15 wire extending through said container and

having one end compressed between said nipple and said ledge; a binding post extending into said container and insulated therefrom, said wire having a portion connected to said binding post; and means connected to said container and binding post and including an electric generator whereby current is supplied to said wire; substantially as described.
